WATER CHAIR

Noble R. Waters, Sr., 2713 Quinn, Fort Worth, Tex.

Filed July 14, 1959, Ser. No. 827,083

1 Claim. (Cl. 9—347)

This invention relates to buoyant floats for use by bathers and has reference to a chair-like structure in which the bather may recline or paddle about in the water. The invention is also capable of other uses, for example, life saving purposes and therapeutic treatments.

An object of the invention is to provide a buoyant chair-like structure for supporting a person in the water, and which structure cannot sink by reason of being punctured.

Another object of the invention is to provide a buoyant chair for the described purpose wherein the seat may be adjustably supported at desired angles relative to the plane of the float for comfort to the person sitting therein and for other reasons, for example, it may be preferred that the seat is parallel with the float when paddling about.

Another object of the invention is to provide an inexpensive construction of synthetic resin, yet provide a float which will not sink in the event of accidental puncture.

Another object of the invention is to provide a buoyant chair made of expanded synthetic resin foam, yet one which is unusually strong and durable.

A further object of the invention is to provide a water chair in which all materials are such that they will not deteriorate for long periods of time even though subjected to fresh or salt water.

These and other objects will become apparent from the following description and the accompanying drawing, wherein:

Figure 1 is a broken perspective view of a water chair embodying the features of the invention.

Figure 2 is a front elevational view of the chair illustrated in Figure 1.

Figure 3 is an enlarged transverse sectional view of the float and showing means for attaching a seat supporting hanger.

The form of the invention shown is comprised of a U-shaped float of expanded foam material of synthetic resin, but it is to be understood that the float may consist of other shapes, for example, square, rectangular or round. The expanded synthetic resin referred to is preferably made of polystyrene pellets which are subjected to heat in a mold; however, it is to be understood that

2

other types of synthetic resin foam may be employed, for example, styrofoam.

Extending through the axial center of the float there is a reinforcing rod 11, the purpose of which is to lend 5 rigidity and safety to the herein described construction and to support a seat member 12. The seat 12 generally conforms with the inner dimensions of the float 10 and is connected therewith by means of metal or other suitable hangers 13, corresponding ends of which have holes 10 therein, not numbered, and are mounted on the reinforcing rod 11. The depending ends of the hangers also are provided with holes, not numbered, through which a nylon or other suitable cord 14 is threaded. The seat 12 is supported by the cord 14 at its forward corners and at its rear center, such supports including pairs 15 of holes through which the cord 13 is placed. The cord 13 is continuous by reason of tying or splicing, one portion of the cord extending across and beneath the forward lower surface of the chair 12, another length 20 of cord extending from the same hanger entering through the adjacent hole 15 in the seat and extending beneath the seat to one of a pair of holes 15 at the rear center thereof, thence upwardly and through the hole into the depending rear hanger 13 and thence to the adjacent hole 25 in the seat and then to a hole in the forward corner of the seat. Such cord arrangement provides for slidable adjustment whereby the plane of the seat 12 may be angularly adjusted relative to the plane of the float.

A person sitting in the seat 12 has his shoulders above 30 the float and whereby he may paddle with his arms or recline if he so desires. When reclining, it will be desirable to have the rear edge of the seat 12 a greater distance from the float than the forward edge. Further, in view of the described construction, it will be apparent that 35 the device is not only strong and durable, but is also one which will not sink by reason of being punctured.

The invention is not limited to the construction herein shown and described, but may be made in various ways within the scope of the appended claim.

40 What is claimed is:

A water chair comprising an elongate float having at 45 least three sides, said float being of foam synthetic resin, a rod embedded in and extending substantially the length of said float along the axial center thereof, a seat generally conforming with the inner dimensions of said float, and spaced therefrom, depending hangers directly connected with said rod at spaced intervals thereon, and flexible supporting means connecting said seat with said hangers.
